UNITED STATES PATENT OFFICE

2,363,141

DENTAL HAND PIECE

Ernest R. Pertics, Lapaz, Ind.

Application February 27, 1943, Serial No. 477,417

1 Claim. (Cl. 32—28)

The present invention relates to new and useful improvements in dental hand pieces, and has for its primary object to provide, in a manner as hereinafter set forth, an instrument of this character comprising novel cooling means, thus promoting patient comfort and consequently facilitating and expediting the work of the operator.

Other objects of the invention are to provide a dental hand piece of the aforementioned character which will be comparatively simple in construction, strong, durable, highly efficient and reliable in use, compact, light in weight, and which may be manufactured at low cost.

All of the foregoing and still further objects and advantages of the invention will become apparent from a study of the following specification, taken in connection with the accompanying drawings, wherein like characters of reference designate corresponding parts throughout the several views, and wherein:

Figure 1 is a view in side elevation of an embodiment of the apparatus.

Figure 2 is a view in side elevation of the hand piece with the upper portion thereof broken away.

Figure 3 is a vertical sectional view through the hand piece, taken substantially on the line 3—3 of Figure 2.

Figure 4 is a view in horizontal section, taken substantially on the line 4—4 of Figure 2.

Referring now to the drawings in detail, it will be seen that reference numeral 1 designates generally a conventional dental engine or unit comprising the usual folding arm 2. Mounted on the arm 2 is a hand piece 3.

The hand piece 3 includes a tubular handle 4 of suitable metal having therein a lining 5 of insulating material. Journaled longitudinally in the tubular handle 4 is a shaft 6. A chuck 7 on one end of the shaft 6 accommodates a dental drill or other tool 8.

Mounted longitudinally in the tubular handle 4 is a coil 9 which encircles the shaft 6. The tubular handle 4 has formed therein a longitudinal, internal channel 10 which accommodates the vapor return lead 11 of the coil 9. The coil

9 receives a refrigerant from a suitable cooling unit 12. As shown in Figures 1 and 3, the coil 9 has inlet and outlet pipes 13 and 14, and the unit 12 has inlet and outlet pipes 15 and 16, respectively connected by a flexible conduit 17 provided with supply and return passages.

It is thought that the operation of the device will be readily apparent from a consideration of the foregoing. Briefly, heat from the work, such as a tooth, is transmitted through the tool 8 to the shaft 6 in the tubular handle 4. The refrigerant from the unit 12, circulating through the coil 9, rapidly absorbs the heat, thereby maintaining the tooth at a comfortable temperature.

It is believed that the many advantages of a dental hand piece constructed in accordance with the present invention will be readily understood, and although a preferred embodiment of the instrument is as illustrated and described, it is to be understood that changes in the details of construction may be resorted to which will fall within the scope of the invention as claimed.

What is claimed is:

25 In combination with a dental hand piece including a tubular handle having an insulating lining, a shaft journaled longitudinally in and projecting beyond one end of said handle, said shaft being disposed axially of and spaced from the handle to provide a cylindrical chamber therebetween, and means for securing a tool on the projecting end of the shaft, a coil for the passage of a refrigerant mounted longitudinally in said chamber of the handle and encircling the shaft, said coil having refrigerant inlet and outlet ends passing out of the other end of the handle and being provided with a straight return lead extending longitudinally of the handle outwardly of said coil, said handle having an internal longitudinal channel in which said return lead is positioned, a cooling unit remote from the hand piece and having refrigerant inlet and outlet pipes, and flexible conduit connections between the inlets and outlets of the coil and the cooling unit.

ERNEST R. PERTICS.
